UNITED STATES PATENT OFFICE.

JEREMIAH. KELLER, OF SANDUSKY, OHIO, ASSIGNOR TO WALDO F. CONVERSE, OF SAME PLACE.

HAY-TEDDER.

SPECIFICATION forming part of Letters Patent No. 311,991, dated February 10, 1885.

Application filed February 23, 1884. (No model.)

To all whom it may concern:

Be it known that I, JEREMIAH KELLER, of Sandusky, in the county of Erie and State of Ohio, have invented new and useful Improvements in Hay-Tedders; and I do hereby declare that the following is a full, clear, and exact description thereof, reference being had to the accompanying drawings, which form a part of this specification.

10 This invention relates to certain new and useful improvements in the construction of hay-tedders; and the invention consists in the peculiar construction of the forks and means employed for operating them, and in the peculiar construction, arrangement, and combinations of the various parts, all as more fully hereinafter set forth.

Figure 1 is a top plan. Fig. 2 is a side elevation. Fig. 3 is a rear elevation, partially in section. Fig. 4 is a detached perspective view of one of the rotating heads and its actuating mechanism. Fig. 5 is a section through $x x$ of Fig. 3.

In the accompanying drawings, which form a part of this specification, A A represent the two traction-wheels, which are mounted upon the axle-arms B, the inner ends of which are journaled in the upper ends of the brackets C, which are in turn rigidly secured to the central bar, D.

F represent two shafts, upon each of which is rigidly secured a circular head, a, near the inner ends of the shafts, while near their outer ends are rigidly secured the heads b, the outer ends of the shafts being journaled in the outer ends, c, of the brackets C, while their inner ends are journaled in a box, G, on the outer end of the central bracket, H. Upon the outer ends of the shafts F there are secured sprocket-wheels I I, which impart motion to the shafts through the medium of chains J J from large sprocket-wheels K, sleeved upon the axles B. Said wheels K are provided with a spring-dog, d, which engages with a ratchet, e, upon the inner ends of the hubs of the wheels A, the whole being so connected that in the forward motion of the machine a rotary motion is imparted to the shafts F. Between each pair of heads a b of these shafts F are properly journaled the three rock-shafts L, upon each of

which is secured a pair of spring tedder teeth or forks, M. The outer ends of these rock-shafts pass through the heads b, and have rigidly secured to them crank-arms h, carrying anti-friction rollers i, which travel in the grooved cams j, formed in the inner faces of the heads c of the brackets C.

Rising from the bar D is a standard, N, which carries a spring-latch, O, adapted to engage with a curved rack-bar, P, upon the draft-frame. By these means the device can readily be partially turned upon the axles B, so as to regulate the height of the tedder-forks from the ground.

As the device is drawn forward a rotary motion is imparted to the shafts F through the connection herein named, and a partial rotary movement is likewise given to the shafts which carry the tedder-forks, causing them to thoroughly perform the functions for which they are designed.

I am aware that it is not new to provide hay-tedders with a single rotating shaft extending the full width of the machine, said shaft carrying a single tedder-reel, and do not broadly claim such as my invention, for in such construction, when the machine is turning a corner or traveling in a curved line, the tedder-reel has the same motion throughout its entire length, which is objectionable, and not absolutely necessary, as that part of the machine on the inner track has a less distance to traverse, and consequently there is no necessity for that part of the tedder-reel on the inner side of the curve to travel as fast as that part on the outer side. By my construction the reel-shaft and tedder-reels are each in length only about half the width of the machine, but together occupy a space equal to the width of the machine, and as each reel-shaft is independently driven from the traction-wheels an unequal motion is given to each tedder-reel in passing around curves in proportion to the radii of said curves, thus economizing power and diminishing the wear of the machine.

What I claim as my invention is—

1. In a hay-tedder, the brackets C, attached to the draft-frame D, each having bearings for a short independent axle-arm, B, at its upper

end, and each provided with a cam-grooved head, *c*, at its other end, in combination with the independently-rotating shafts *F*, journaled between said heads, and means whereby an independent motion is imparted to each shaft, substantially as and for the purpose specified.

2. In a hay-tedder, the brackets *C*, secured to draft-frame *D* at one end, in combination with the bracket *H*, attached to the draft-frame, and provided with a bearing, *G*, shafts *F*, independently journaled between said brackets, one on either side of the bracket *H*, and carrying the rock-shafts *L*, and means for independently rocking the shafts *L*, as and for the purposes set forth.

3. In a hay-tedder, the brackets *C*, secured to the draft-frame at one end, and provided

with cam-grooved heads *c* at their free ends, in combination with the rotating shafts *F*, independently journaled in and between said heads *c*, the heads *a b*, secured to said shafts and rotating therewith, rock-shafts *L*, journaled in said heads, and provided with tedder-forks *M*, crank-arms *h*, attached to the outer ends of said shafts *L*, and carrying the anti-friction rollers *i*, running in the cam-groove in the heads *c*, and means for imparting an independent motion to the shafts *F* from the drive-wheels, substantially as described.

JEREMIAH KELLER.
